UNITED STATES PATENT OFFICE.

IRA E. STUMP, OF CLEVELAND, OHIO, ASSIGNOR OF ONE-HALF TO OBED C. BILLMAN,
OF CLEVELAND, OHIO.

MECHANICAL MOVEMENT.

1,259,926.

Specification of Letters Patent. Patented Mar. 19, 1918.

Application filed November 20, 1916. Serial No. 132,329.

To all whom it may concern:

Be it known that I, IRA E. STUMP, a citizen of the United States, residing at Cleveland, in the county of Cuyahoga and State 5 of Ohio, have invented certain new and useful Improvements in Mechanical Movements, of which the following is a specification.

My invention relates to improvements in 10 mechanical movements, and more particularly to that class or type in which reciprocatory movement is converted or transformed into rotary movement through the medium of a suitable spiral suitably arranged relative to and cooperating with the 15 adjacent parts.

The primary object of the invention is the provision of a generally improved mechanical movement of the class or type above indicated, capable of a large variety of uses and applications, as well as one which will be exceedingly simple in construction, cheap of manufacture, and efficient in use.

A further object is the provision of an improved spiral member interposed between the reciprocatory and rotary members together with an improved method of mounting the spiral member and bringing the same into and out of clutched relation with one 30 of said members upon the initial advance and return movements or strokes of the said reciprocatory member whereby rotary motion will be imparted to the rotary member.

A still further object is the provision of an improved spiral and spiral clutch together with improved means of mounting and combining the same in coöperative relation to the various working parts in the particular article or device in which the improved movement may be embodied.

With the above mentioned and other ends in view, the invention consists in the novel construction, arrangement, and combination of parts, illustrated in some of its embodiments in the accompanying drawing and particularly pointed out in the appended claims.

Referring to the drawings, forming a part of this specification, Figure 1, is a central 50 longitudinal sectional view of a screw driver embodying the improved mechanical movement, the rotary member and spiral being shown in clutched or locked engagement with the reciprocatory or handle member 55 when the latter is in its most advanced posi-

tion whereby the blade or shank portion of the screw driver is locked for use as an ordinary screw driver.

Fig. 2, a similar view, the rotary or shank portion of the tool being in its intermediate 60 position whereby the same is actuated and given a rotary motion by the spiral through the advance or forward movement of the reciprocatory member or handle.

Fig. 3, a view of the spiral member detached. 65

Fig. 4, a similar view of the shank or rotary member detached.

Fig. 5, a cross sectional view taken on line 5—5 of Fig. 1. 70

Fig. 6, a view of a modification of the improved movement applied to or embodied in a spinning top. 75

Fig. 7, a view of the same detached from the top body and showing the spiral member moved longitudinally out of engagement with the rotary member during the return movement of the reciprocatory member preparatory to giving the spiral and rotary members a new working impulse. 80

Fig. 8, a longitudinal sectional view of a handle or reciprocatory member embodying a further modified form for use in connection with an article or utensil, such as an egg beater, or the like. 85

Fig. 9, a similar view of the same, the reciprocatory or handle member being in advanced position preparatory to its return movement whereby the spiral member will be moved longitudinally out of engagement 90 with the reciprocatory member for a new working impulse and permit of the continued rotation of the rotary member until the latter is given a new working impulse by the reengagement of the spiral member. 95

Fig. 10, a similar view in which a second reversely arranged spiral member is mounted outside of the first spiral whereby a continued driving motion is imparted to the rotary member during the return as well as the 100 advance or forward movement of the reciprocatory or handle member.

Fig. 11, a similar view in which the inner spiral member is in action and in clutched relation to the reciprocatory member while 105 the outer spiral member is out of action and out of clutched position (in contrast to the positions shown in Fig. 10) and preparatory to the return of handle member for releasing the inner spiral member and bring- 110

ing the outer spiral member into action as shown in Fig. 10.

Fig. 12, a cross sectional view of the same taken on line 12—12 of Fig. 10.

5 Fig. 13, a view of the outer spiral member removed.

Fig. 14, a view of the inner spiral member removed.

Fig. 15, a view of a further modification 10 in which the spiral member is fixed upon the rotary member and is thrown into and out of engagement with the reciprocatory or handle member upon the initial advance and return movements of the latter, respectively, through the medium of a modified or 15 improved form of clutch carried by the reciprocatory member.

Fig. 16, a cross sectional view of the same taken on line 16—16 of Fig. 15, the ball of 20 the improved clutch, however, being in clutched position.

Similar numerals of reference designate like parts throughout all the figures of the drawings.

25 The improved mechanical movement comprises a reciprocatory or handle member 1, and a rotary member 2, and as a means of transmitting rotary motion to the rotary member 2, through the reciprocation of the reciprocatory member 1, a spiral 3, is interposed between the members 1, and 2, in coöperative relation thereto, and in accordance with the particular demands or requirements of the article or device in which the 30 improved movement may be embodied.

As a means of bringing the spiral member 3, into and out of engagement with one of the members upon the initial advance and return movements of the reciprocatory or 40 handle member 1, whereby rotary motion is imparted through said spiral 3, to the rotary member 2, and the latter and said spiral member are released upon and during the return movement of the reciprocatory member, a suitable clutch or engaging member 4, may be provided.

The elements 1, 2, 3, and 4, may be of any suitable and convenient form as suggested in the drawings, it being obvious that the improved movement is capable of a variety of uses and applications of which those herein shown and described are merely illustrative.

For example, the reciprocatory or handle member 1, may be mounted upon or in a suitable guide or support 5, and the latter may take various forms, as for example,—as a surrounding tube or casing as shown in Figs. 6, and 7, of the drawings, and in Figs. 60 15, and 16, of the drawings, or in the form of supporting guide or frame members as shown in Figs. 8, to 11, inclusive, thereof.

As shown in Figs. 1, to 14, inclusive, of the drawings, the spiral 3, may be formed 65 of the single length of spirally wound sheet

metal suitably spaced apart to form the spiral grooves or recesses 3^a, and when so formed is adapted to have a circumferential and a limited longitudinal movement between the reciprocatory and rotary members 1, and 2, whereby the clutch 4, is adapted to come into and out of engagement with one of said members upon the initial advance and return movements of the reciprocatory member.

75 The clutch 4, may take the form of a pair of engaging prongs adapted to be seated in and to engage with a suitable stationary portion of the reciprocatory or handle member 1, as shown in Figs. 1, to 5, inclusive, and Figs. 8, to 11, inclusive, of the drawings, said prongs, in the first instance, engaging on opposite sides of a cross pin 4^a, and in the second instance, engaging in a pair of openings 4^b, in the top of the handle 1. If desired, however, the reciprocatory or handle member 1, may extend within the spiral member 3, and operate the latter through the medium of a stud or projection 1^a, as illustrated in Figs. 6, and 7, of the drawings, and in which instance, the rotary member 2, is attached to (or may form a part of) a suitable rotary member as for example,—a top body 2^a. In this instance, the rotary member 2, is provided with a pair of openings 4^c, to receive the clutch projections 4.

As a means of holding the rotary member or shank 2, of the screw driver in a stationary or locked position when the reciprocatory or handle member 1, is fully advanced so that the shank or blade 2, of the screw driver may be used as an ordinary screw driver, or in other words, without bringing the spiral feature into operation, the top of the shank or rotary member 2, may be provided with a central notch or recess 2^e, to receive and contain and interlock with the cross pin 4^a, as shown most clearly in Figs. 1, and 5, of the drawings.

100 The rotary member 2, in the forms shown in Figs. 1, to 5, inclusive, and in Figs. 8, to 12, inclusive, is provided with a stud or projection 2^d, adapted to travel within or traverse the spiral recesses 3^a, in an obvious manner, and as a means of retracting or returning the reciprocatory or handle member 1, to its initial or retracted position in the forms shown in Figs. 8, to 12, inclusive, of the drawings, a compression spring 6, may 105 be mounted within the handle 1, and between the head of the latter and a support or head 5^a, of the stationary support or frame member 5, and operating in an obvious manner.

110 In the form shown in Figs. 10, and 11, however, the spring 6, may be dispensed with and in such form it will be observed that an outer spiral member 3^b, is provided, said spiral being oppositely arranged and 115

disposed and being adapted to be brought into engagement with the stud of projection 2^a, of the rotary member 2, upon the return or retraction of the reciprocatory or handle member 1, so that the inner and outer spirals are alternately brought into and out of operative engagement with the rotary member 2, and the latter is driven during both the advance and return movements of the reciprocatory or handle member 1, as hereinbefore explained. The form of the outer spiral member being the same as the inner, it need not be explained in detail, and it will be observed that the clutch projections 4, thereof fit into a pair of openings 4^a, in the lower end of the handle and perform a function similar to those of the openings 4^b, at the opposite end of the handle as hereinbefore explained.

20 In the form shown in Figs. 15, and 16, of the drawings, the spiral 3, comprises two lengths of wire wound about the rotary member 2, in a stationary or fixed manner and the spiral is brought into and out of engagement with the handle 1, upon the initial advance and return movements of the same, respectively, through the medium of an improved clutch carried upon the handle member 1, said clutch comprising a ball 25 clutch 7, loosely mounted in a casing 8, the latter being provided with openings 8^a, to receive and to traverse the spiral 3, and forming an annular ball race-way 8^b, so that at the end of the working stroke of the handle member 1, or upon the initial return of the latter the force of gravity will hold the ball 7, within the race-way 8^b, and permit the convolutions of the spiral 3, to travel about and carry with them the ball 7, in 30 the ball race-way 8^b, but upon the initial advance or return movements of the handle the ball clutch 7, will find its way into one of the recesses 8^c, (see Fig. 16) so that upon the return or downward movement of the 35 handle 1, the ball will remain seated between one of the recesses 8^c, and the adjacent spiral and cause the latter to be rotated until pressure is released to permit the ball to drop by gravity and find its way into the ball race-way 8^b.

It will also be observed that in all instances the axially located rotary member 2, not only projects from or extends beyond one end of the reciprocatory and spiral members but that its end or terminating bearing portion is arranged within the common axial planes of said members.

From the foregoing description taken in connection with the accompanying drawings, the advantages and operation of my invention will be readily understood.

Having thus described some of the embodiments of my invention, what I claim and desire to secure by Letters Patent, is,—

65 1. A mechanical movement, comprising a reciprocatory member, a rotary member pro-

jecting from one end thereof, a spiral interposed therebetween and surrounding one of said members, and means connecting said spiral to said members comprising a clutch 70 adapted to be engaged and disengaged by the movements of said reciprocatory member.

2. A mechanical movement, comprising a reciprocatory member, a rotary member carried by and projecting from one end thereof, a spiral, and means connecting said spiral with said members including a clutch adapted to be engaged by one of said members upon the reciprocation of the other and whereby a rotary motion is imparted to 80 said rotary member through said spiral.

3. A mechanical movement, comprising a reciprocatory handle member, a rotary member projecting from one end thereof, a spiral surrounding one of said members and covered by the other member, and means for bringing said spiral member into clutched relation with one of said members upon and during the reciprocatory movement of one of said members whereby rotary motion is 90 imparted by said spiral member to the other member.

4. A mechanical movement, comprising a reciprocatory handle member, a rotary member depending axially therefrom, a spiral 95 member interposed between said reciprocatory and rotary members, and means for bringing said spiral member into and out of clutched relation with one of said members upon the initial downward and return 100 strokes of said reciprocatory member, respectively, whereby rotary motion is imparted to said rotary member through said spiral member.

5. A mechanical movement, comprising a 105 reciprocatory handle member, a rotary member carried thereby and depending therefrom, a spiral member movably interposed between said members, and covered by said handle member, and means for moving and bringing said spiral member into and out of clutched relation with one of said members upon the initial downward and return strokes of said reciprocatory member, respectively, whereby rotary motion is 110 imparted to the other member through said movements of said spiral member.

6. A mechanical movement, comprising a reciprocatory handle member, a rotary member projecting axially from one end thereof, and a longitudinally and circumferentially movable spiral sleeve member covered by one of said members and carrying a clutch adapted to be thrown into and out of engagement with one of said members upon the initial advance and return movements of said reciprocatory handle member, respectively, whereby rotary motion is 125 imparted to said rotary member and the latter and said spiral member are released during 130

the return movement of said reciprocatory member.

7. A mechanical movement, comprising a reciprocatory handle member, a rotary member, a spiral sleeve member longitudinally and circumferentially movable therebetween, and means for limiting the longitudinal movement of and for bringing said spiral member into and out of engagement with one of said members upon the initial advance and return movements of said reciprocatory member whereby rotary motion is imparted through said spiral to said rotary member and the latter and said spiral member are released upon and during the return movement of said reciprocatory member.

8. A mechanical movement, comprising a reciprocatory handle member, a rotary member projecting from one end thereof, a longitudinally and circumferentially movable spiral sleeve member interposed between and co-operating with said members and extending substantially throughout the length of said handle and provided with a clutch movable into and out of engagement with one of said members upon the initial working and return movements of said reciprocatory member, respectively, whereby rotary motion is imparted to said rotary member through said spiral member and the latter is released and permitted to move freely and independently when not engaged by said reciprocatory member.

9. A mechanical movement, comprising a reciprocatory handle member, a rotary pendant member terminating in the axial plane of said handle member, a spiral sleeve loosely mounted between said members and provided with a clutch adapted to be brought into and out of engagement with one of said members upon the initial advance and return strokes of said reciprocatory member, respectively, whereby rotary motion is imparted to said rotary member upon and during the advance stroke of said reciprocatory member and whereby at the end of said advance stroke and upon the return of said reciprocatory member the latter will be moved out of engagement to permit of the continued rotation of said rotary member.

10. A mechanical movement, comprising a support, a reciprocatory handle member thereon, a rotary member extending from and having a terminating bearing point within the axial planes of said support and reciprocatory handle member, a spiral, and a movable clutch carried on and operated by one of said members for bringing said spiral into and maintaining the same in engagement with one of said members upon and during the reciprocation of said reciprocatory member whereby rotary motion is imparted by said spiral to said rotary member.

11. A mechanical movement, comprising a supporting member, a reciprocatory handle member, and a rotary member mounted on said supporting member and terminating in a bearing portion within the axial planes of said supporting and handle members, a spiral member inclosed by one of said members and interposed between said reciprocatory and rotary members, and a longitudinally and circumferentially movable clutch for bringing said spiral member into and out of engagement with one of said members upon the initial downward and return strokes of said reciprocatory member whereby rotary motion is imparted to said rotary member through said spiral member.

12. A mechanical movement, comprising a reciprocatory handle member, a rotary member axially located therein and extending from one end thereof, a spiral sleeve member longitudinally and circumferentially movable between said reciprocatory and rotary members and extending substantially coincident to one of said members, a support for said last mentioned members, and clutch and stop means for moving said spiral sleeve member longitudinally into and out of engagement with one of said members upon the initial advance and return movements of said reciprocatory member, respectively, whereby rotary motion is imparted to said rotary member and the latter and said spiral member will be free upon and during the return movement of said reciprocatory member.

13. A mechanical movement, comprising a supporting member, a reciprocatory handle member thereon, a rotary member axially located in and projecting from said supporting member, a spiral member, and a circumferentially and longitudinally movable clutch carried on and operated by one of said members for bringing said spiral into and maintaining the same in engagement with one of said members upon and during the reciprocation of said reciprocatory handle member whereby rotary motion is imparted by said spiral to said rotary member.

14. A mechanical movement, comprising a support, a reciprocatory handle member, a rotary member mounted in and projecting from one end of said support and terminating in a bearing portion within the axial plane of said handle member, a spiral member interposed between said members, and a longitudinally and circumferentially movable clutch carried by one of said members for bringing said spiral member into and out of engagement with one of said members upon the initial downward and return strokes of said reciprocatory member whereby rotary motion is imparted to the rotary member through said spiral member and the

latter is released during the return movement of said reciprocatory member.

15. A mechanical movement, comprising a reciprocatory handle member, a rotary member projecting from one end of said handle member and terminating in the bearing portion within the axial plane of the latter, a spiral member longitudinally and circumferentially movable between said reciprocatory and rotary members, a guiding and bearing support for said last mentioned members, respectively, and means for moving said spiral member longitudinally into and out of engagement with one of said

members upon the initial advance and return movements of said reciprocatory member, respectively, whereby rotary motion is imparted to said rotary member and the latter and said spiral member will be free upon and during the return movement of 20 said reciprocatory member.

In testimony whereof I have affixed my signature in the presence of two witnesses.
